UNITED STATES PATENT OFFICE.

MICHAEL POWER, OF TORONTO, CANADA.

CONVERTIBLE CAR.

SPECIFICATION forming part of Letters Patent No. 749,579, dated January 12, 1904.

Application filed August 17, 1903. Serial No. 169,771. (No model.)

To all whom it may concern:

Be it known that I, MICHAEL POWER, of the city of Toronto, in the county of York, in the Province of Ontario, Canada, have invented 5 certain new and useful Improvements in Convertible Cars, of which the following is a specification.

My invention relates to improvements in convertible cars; and the object of the invention is to construct a simple, cheap, and compact form of car of this class in such a manner as not to depart from the general design of the ordinary form of open or closed car; and it consists, essentially, of the main frame 15 formed with the vertical supporting-posts having side rabbets formed therein, a series of sections designed to be held within the said grooves between the running-board and the upper bounding-rail and suitable turn-buttons 20 pivotally secured to the said posts for holding the sections in place, a series of seats supported upon suitable standards within the car and means for securing the seats to the said standards whereby the seats may be either arranged 25 crosswise of the car as used in the summer cars or arranged longitudinally of the car end to end to each side of the car as arranged for winter use, a detachable step or running-board supported on suitable hangers 30 secured beneath the sill of the car, the said running-board being provided with openings or cut-away portions, a sliding plate designed 35 to cover the said opening and a bearing-spring secured to the running-board against which the said plate is designed to be held, the parts being arranged and constructed in detail as hereinafter more particularly explained.

Figure 1 represents a general perspective view of my car, partially broken away and in 40 section, the front portion of the car being arranged for summer use and the rear portion being arranged for winter use. Fig. 2 represents a cross-section through the front portion of the car, showing the seats arranged crosswise thereof. Fig. 3 represents a sectional plan view of a portion of the car, showing a seat as arranged in Fig. 2. Fig. 4 represents a cross-section through the rear portion of Fig. 45 1. Fig. 5 is a sectional plan view showing the seats arranged as in Fig. 4. Fig. 6 is a detail 50

view of the removable wall-section. Fig. 7 is a detail of the removable legs supporting the seats as arranged for winter use. Fig. 8 is a detail of the end plate for the seats. Fig. 9 is a detail of a portion of the step and the 55 movable plate.

In the drawings like letters of reference indicate corresponding parts in each figure.

A is the floor of the car, provided with the usual sills *a*. 60

B is the roof, and C is a longitudinal side timber thereof.

D represents the vertical supporting-posts of the roof, secured at their lower ends to the sill *a* and at their upper end to the timber C, 65 forming part of the roof of the car.

C' is a bounding-strip secured to the timber C and provided with a recess *c'*.

The vertical posts D are provided with the guiding-grooves *d*, in which the cross-bars of 70 a blind are designed to run in the usual manner. The posts D are also provided with front ribs *d'*, which form rabbets *d''* to each side thereof, into which the sections of the wall of the car are designed to fit. Between the guiding-grooves *d* and the rabbets *d''* on the side of the post are secured the hand-rails *d''*. It will be seen by this arrangement that when the blind is drawn down the hand-rails would be left to the outside in position for use by any person 75 80 on the running-board of the car.

E represents the removable wall-sections, composed of a rectangular frame *e*, in which the usual window and sash *e'* are fitted, the lower portion of the section being covered 85 with suitable sheeting, as used in the wall of an ordinary closed car. The inner edges of the frame are provided with suitable strips of felt packing, as shown in Fig. 6.

E'' are turn-buttons centrally secured by 90 the bolts *e'' e'* to the central rib *d''* of the vertical post D. These turn-buttons serve to hold the wall-sections of the car in place in the rabbets *d''*.

F represents metallic standards secured at 95 the side of the car to the floor and to the vertical posts D. The metallic standards F are provided with vertical ribs *f*, designed to extend to each side of the vertical standard, thereby forming a support for the same. 100

f' represents lugs extending outwardly from the inner side of the metallic standard, provided with slots f'' .

5 G represents the seats, composed of the longitudinal bars g and longitudinal slats g' .

g^2 represents metallic end plates formed with the recess g^3 and the ribs g^4 and end lug g^5 .

10 The ends of the longitudinal bars g are suitably secured to the lugs g^5 , and longitudinal slats g' are designed to rest and be secured upon the ribs g^4 of the end plate.

g^6 represents longitudinal truss-rods which connect the end plates g^2 together, and thereby bind and brace the whole seat together.

15 g^7 represents downwardly - extending L-shaped hooks secured in proximity to the end of the seat. These hooks are designed to extend downwardly through the slots f'' of the lug f' when the seats are arranged crosswise 20 of the car. The hooks as soon as they have been passed through the slots may be turned one-quarter turn, so as to lock the seat in position. It will be seen by this construction that the seats being supported upon the lugs 25 f' at each end and being braced by the truss-rods g^6 it is unnecessary to use any legs or other supports, thereby leaving the floor of the car perfectly clear for the purpose of cleaning or for any other purpose desired.

30 G' represents the usual backs of the seats, which are pivotally connected in the usual manner at their ends to the vertical posts D of the car. When it is desired to use the car for winter, these backs are removed and stored 35 away. The seat is detached from the lugs f' and is arranged parallel with the side of the car and connected to the standards F in the following manner:

G^2 is the back of the seat used in the winter-40 car, which is placed against the wall of the car, the bottom thereof resting on the lugs f' .

h is a draw-bolt connected to the back of the back of the seat and designed to extend downwardly through the slots f'' of the lugs f' and be secured by the nut h^2 in a plate h' , secured 45 beneath the seat. By this connection it will be seen that the level of the seat is lowered slightly, so as to enable a cushion to be used upon the seat, as shown in Figs. 1 and 4.

50 I represents the supporting-legs of the seats of the winter-car, designed to be secured beneath the abutting ends of the seats to the front thereof. The legs I are formed with a reduced upper portion i , designed to extend 55 into a casting i' , provided with slots i'' , through which the L-shaped hooks g^7 are designed to extend. The lower end of the leg is designed to extend into a suitable socket i^3 , provided with a bayonet-slot i^4 , into which is designed 60 to extend a projection-pin i^5 , secured in the leg. By this means it will be seen that the seat is locked in position to the floor and that in cleaning the car it will not be liable to become displaced.

65 Beneath the sill is secured a running-board

a' , upon which the bottom of the wall-sections F are designed to rest. The running-board is designed to extend upwardly beyond the surface of the wall of the car, so as to provide a side rail for the car.

70 Beneath the running-board a' is secured a T-shaped angle-bar a^2 . To the angle-bar a^2 is secured the L-shaped hanger a^3 , provided with a brace a^4 . Upon the hanger a^3 is supported the step or running-board a^5 . To prevent the wheels of the car in a double-truck car as the car is passing round a curve from coming in contact with the step itself, I provide the following device:

75 a^6 represents cut-away portions formed in 80 the step a^5 , and to each side of this portion I secure a leaf-spring a^7 .

85 J represents sliding plates held within the guides a^8 , forming part of the step a^5 , and are provided with depending pins j , against which the leaf-spring a^7 is designed to bear. It will be seen that as the car passes round the curve the wheels will come in contact with these plates, pressing them outwardly against the spring, and that when the curve is passed 90 the plates will be carried back into position by the said spring.

When it is desired to change the car from the form used in summer to that used in winter, it is merely necessary to detach the cross-seats and arrange them longitudinally of the car, as described, then to insert the wall-sections between the vertical posts of the car-frame and to turn the buttons e^3 , so as to hold them in place, and to remove the detachable 100 step a^5 . It will also be seen that when the car is being used for summer purposes the running-board a' will not only serve the purpose of a side rail, but also of a step.

105 It will be seen from this description that I have constructed a car which may be adapted both for summer and winter use and will be simple, cheap, and compact in construction, and the general appearance of the car will not be altered from the general design of an ordinary summer or winter car, and that the car when used for winter will be warm and comfortable. It will also be noticed that the buttons E' and E^2 are provided on the interior surface with the rubber pads E^3 . By this 110 means the sections are kept perfectly tight in place, and thereby prevent any danger of them becoming loose or creaking or the surface of the car becoming in any way marred by them.

115 What I claim as my invention is—

120 1. In a convertible car the combination with the main frame provided with a series of supporting-posts, a series of supporting-standards arranged parallel to the sides of the car at the inside of the posts, suitable seats and detachable means for connecting the seats to the said standards either arranged crosswise of the car or longitudinally parallel to the sides thereof as and for the purpose specified.

125 2. In a convertible car the combination with 130

the main frame, of a series of supporting-posts, a series of supporting-standards arranged parallel to the side of the car having inwardly-extending lugs, a series of seats and means for securing the said seats to the lugs as and for the purpose specified.

3. In a convertible car the combination with the main frame provided with the vertical supporting-posts, of a series of standards arranged parallel with the side of the car having inwardly-extending slotted lugs, a series of L-shaped hooks secured in proximity to the ends of the seats designed to extend downwardly through the said slots as and for the purpose specified.

4. In a convertible car the combination with the supporting-standards for the seats, of a seat composed of a series of longitudinal bars, a metallic end plate located to each end of the seat to which the said bars are secured and truss-rods connecting the said end plates together as and for the purpose specified.

5. In a convertible car the combination with the main frame provided with the vertical supporting-posts, a series of standards arranged parallel with the side of the car having inwardly-extending slotted lugs, suitable seat-backing designed to rest upon the said lugs, a depending bolt secured at its upper end to the said seat-backing designed to extend downwardly through the slotted lug, a seat arranged parallelly with the side of the car through which the bolt is designed to extend and be secured and supporting means for supporting the front of the seat as and for the purpose specified.

6. In a convertible car the combination with the main frame provided with a series of supporting-posts, a series of supporting-standards arranged parallel with the side of the car, suitable seat-backing supported upon the said standard, a series of seats arranged parallel with the side of the car, suitable hangers secured to the said seat-backing connected at their lower ends to the rear portion of the seat, a series of detachable supporting-legs designed to extend beneath the abutting ends of the seats to the inside thereof as and for the purpose specified.

50 7. In a convertible car the combination with the main frame provided with a series of supporting-posts, a series of supporting-standards arranged parallel with the side of the car, suitable seat-backing supported upon the said standard, a series of seats arranged parallel with the side of the car, suitable hangers secured to the said seat-backing connected at their lower ends to the rear portion of the seat, a series of detachable supporting-legs designed to extend beneath the abutting ends of the seats to the inside thereof and locking means for securing said leg to the floor of the car as and for the purpose specified.

8. In a convertible car the combination with the main frame provided with a series of sup-

porting-posts, a series of supporting-standards arranged parallel with the side of the car, suitable seat-backing supported upon the said standard, a series of seats arranged parallel with the side of the car, suitable hangers secured to the said seat-backing connected at their lower ends to the rear portion of the seat, a series of detachable supporting-legs designed to extend beneath the abutting ends of the seats to the inside thereof a socket secured to the floor of the car provided with a bayonet-slot and a pin extending outwardly from the said leg into the said slot as and for the purpose specified.

9. In a convertible car the combination with a main frame provided with a series of vertical supporting-posts having rabbets formed therein and a suitable sill for supporting the floor of the car to which the said posts are secured, a running-board secured beneath the sill and extending laterally therefrom beneath the ends of the post, and a series of wall-sections designed to fit into the rabbets formed in the posts and resting on the said running-board and means for securing the said sections in place, said running-board serving as a step approximately in line with the bottom of the sill as and for the purpose specified.

10. In a convertible car the combination with the main frame provided with a series of vertical supporting-posts having side rabbets formed therein and a suitable sill for supporting the floor of the car to which the said posts are secured, a running-board secured beneath the sill and extending outwardly therefrom beneath the ends of the posts, a series of wall-sections designed to fit into the rabbets formed in the posts and to rest on the running-board and a series of turn-buttons secured centrally to the vertical posts of the car designed to extend over the edge of the wall-section as and for the purpose specified.

11. In a convertible car the combination with the main frame of the car provided with a series of vertical supporting-posts having rabbets formed therein and a suitable sill for supporting the floor of the car, a step or running-board secured beneath the sill and designed to extend beneath the vertical posts a bounding strip or rail secured to the top of the frame of the car beneath the eave of the roof, a series of wall-sections designed to be inserted beneath the said rail and into the rabbets formed in the vertical supporting-posts and to be supported upon the running-board or step, a suitable packing designed to be inserted within the edge of the inner face of the section, and a suitable packing secured to the upper end of the section designed to abut against the lower face of the bounding-rail and a series of turn-buttons secured centrally to the vertical posts of the car and designed to extend over the sides of the wall-sections as and for the purpose specified.

12. In a convertible car the combination

- with the main frame provided with a series of vertical supporting-posts having a rabbet and a guiding-groove located in proximity to the inner edge thereof, a suitable sill for supporting the floor of the car, a running-board secured beneath the sill designed to extend beneath the said supporting-posts, a series of car-wall sections designed to be inserted within the said groove, means for securing the
- 5 10 said sections within the groove and a series of hand-rails secured to the side of the posts of the car between the inner face of the wall-section and the guiding-groove as and for the purpose specified.
- 15 20 25 13. In a convertible car the combination with the side supporting the sill for the floor of the car, of a running-board secured beneath the said sill extending outwardly past the face of the side of the car, a series of depending hangers secured beneath the same and a second running-board secured to the said hangers, the running-boards forming a pair of steps one above the other and disposed laterally in respect to the sill as and for the purpose specified.
14. In a convertible car the combination

with the side sill for supporting the floor, of a series of depending hangers secured to the said sill, of a running-board supported thereon having cut-out portions therein, a covering 30 for the said cut-out portions held within suitable guides forming part of the step and a resilient resisting means whereby the said plate is held against the inner side of the step as and for the purpose specified. 35

15. In a convertible car the combination with the side sill for supporting the floor, of a series of depending hangers secured to the said sill, of a running-board supported thereon having cut-out portions therein, a covering 40 for the said cut-out portions held within suitable guides forming part of the step and downwardly - extending projections formed upon the said plate, a leaf-spring secured beneath the running-board against which the 45 said projections are designed to bear as and for the purpose specified.

MICHAEL POWER.
